OF SEATTLE, WASHINGTON

GRINDING TOOL

Application filed September 19, 1929. Serial No. 393,616.

This invention relates to improvements in grinding tools and more especially to a grinding tool adapted for grinding operations in the construction of aircraft.

It is a matter of great difficulty to build airplane fuselages so exactly that all parts will occupy precisely the positions and planes which it is intended they should occupy. The engine ring, for instance, may be slightly inclined relative to the longitudinal axis of the fuselage, yet to allow the engine to be mounted thereon in such manner that its axis is inclined, even slightly, relative to the axis of the fuselage, would seriously impair the performance of the airplane and shorten its life, if it did not render it unsuitable for flying. It is necessary to secure bosses on the engine ring, projecting forwardly, to which the engine is secured, and which afford a means for seating the engine with its axis exactly in line with or parallel to the longitudinal axis of the fuselage. The ends of such bosses must be ground off or otherwise removed in a plane exactly at right angles to this axis, notwithstanding any departure of the engine ring from such a plane. It is the principal object of this invention to provide a device of this character which can be mounted upon the forward end of an airplane fuselage, and moved about a circle to grind away all such bosses evenly, to form a seat for the engine that will be at right angles to the longitudinal axis of the airplane.

Since a rotary grinder which merely moves in one path, whether about a circle or radially, or in some other single direction, will leave a concave surface, not a flat one, it is necessary to give such a grinder, as it moves over each one of the bosses, a compound movement. Hence, another object of the invention is to advance the grinder so that its line of contact with the work will in effect move radially as well as circularly with respect to the work.

These and other objects will appear as my invention is more fully hereinafter described in the following specification, illustrated in the accompanying drawings and finally pointed out in the appended claims.

In the drawings:

Figure 1 is a top plan view of an airplane fuselage showing my improved form of grinding tool in operative engagement therewith.

Figure 2 is a side elevation of Figure 1.

Figure 3 is a front view of Figure 2, showing in dotted lines the operative range of the grinder.

Figure 4 is an enlarged view of a hand wheel.

Figure 5 is an enlarged detail view of an engaging means for the hand wheel with one of the gears.

Referring now more particularly to the drawings:

Reference numeral 1 indicates the forward end of an airplane fuselage to which is secured the usual engine mount for a radial air cooled engine. The engine mount is in the form of an apertured ring 2 having bosses 3 around the apertures. The engine bolts pass through the apertures and are provided with nuts on the inner side of the ring. As the nuts are advanced on the threads of the bolts, the engine is of course drawn tight against the bosses and it is therefore necessary that the length of the bosses be such, without respect to the amount of their projection from the ring, that they will be in a plane perpendicular to the axis of the fuselage, to form an even bed for the engine.

A hub 6 is centrally located with respect to the ring 2 by means of radially extending spokes 7 which bear against the ring 2 and which are provided with studs 7A to bear against the inner periphery of the ring. The ends of the spokes are provided with adjusting screws 7B which are tipped with brass plugs 7C which bear against the ring when

the screws are advanced on their threads.

By such means the plane of rotation of the working face of a grinding tool 13, mounted for rotation upon a base established by the position of the spokes 7, as will appear hereafter, can be adjusted to coincide with a plane at right angles to the longitudinal axis of the fuselage, and is not controlled by the plane of the ring 2. If the ring 2 is canted relative to a plane perpendicular to the longitudinal axis of the fuselage, the screws 7B will so adjust the spokes 7 (of which there are at least three) that this canting will be compensated for, and the working face of the grinder will always lie only in a true perpendicular plane.

For supporting the spokes 7 and their related parts in position against the ring 2 after adjustment into such a perpendicular plane, a disc 9 is provided. Extending radially from the disc are a plurality of arms 10 which are adapted to engage with the structural parts of the fuselage as shown in Figures 1 and 2. An adjusting screw 11 is threadedly mounted through the disc 9 and is adapted to exert pressure against the hub 6. The hub is hollow to rigidly support a shaft 8.

Rotatably mounted on the shaft 8 is a platform 11A. An electric motor 12, driving a grinding wheel 13, is slidably mounted to the top of the platform, and can be traversed thereon by means of a threaded shaft 14 which is provided at its outer end with a hand wheel 15 for convenience in moving the motor back and forth across the platform. The grinding wheel is provided with a guard 15A which is bolted to the motor. An arm 16 extends downwardly from the platform 11A and carries a counterweight 17. The platform is also slidable axially of the shaft 8 and can be set up to cause the grinder to take off more material from the ends of the bosses after it has ground down to the limit of a given setting, by means of a threaded shaft 17A and hand wheel 17B. Fixed to the shaft 8 is a gear 18 intermeshing with a gear train, consisting of gears 19, 20, 21, 22, 23, and 24, and a ratchet wheel 25. The wheels 24 and 25 are secured together by means of screws 26 but can rotate independently of the hand wheel which is keyed or otherwise fastened to the shaft 14. Mounted on one side of the hand wheel 15 and located directly over the ratchet wheel 25 is a vertical bearing 26A which is adapted to slidably and pivotally support a pawl 27. A pin 28 is carried by the pawl and a spring 29 is interposed between the pin and the vertical bearing to keep the pawl under spring tension at all times. In the dotted line position shown in Figure 5 the pawl is clear of the ratchet wheel 25 and the hand wheel 15 is free to be rotated for manual adjustment independently of the gear train. In the full line

position the pawl is engaged with the teeth, and when so engaged the hand wheel will rotate with the ratchet wheel 25 when the platform is swung in one direction, and on the back swing the pawl will ride over the teeth due to the slant on the back side of the pawl, as shown in Figure 5.

At the outset of a grinding operation, the device having been set up so that the working face of the rotary grinder 13 swings in a plane perpendicular to the longitudinal axis of the fuselage, and the motor and grinder being at one limit of their traversing movement (the inner limit, for instance, where the working face of the grinder is the least radial distance from the shaft 8), the grinder is brought into contact with the highest of the bosses 3. It bites into the inner face thereof, and as the end of this boss wears away, the radial distance from the line of contact of the working face with the boss, to the axis of the shaft 8, must be increased. This can be brought about by traversing the motor and grinder along the platform 11A, which has the effect of moving outward the line of contact of the grinder with the work.

Such traversing can be accomplished by swinging the motor and grinder, and its platform 11A and the counterweight 17, from side to side, as is indicated by the dotted lines in Figure 3. The gear wheel 18 being secured to the shaft 8 of course does not rotate but the gear train intermeshing with it is put into motion, and the ratio of the gearing is such that during the swing of the motor, approximately to the limits indicated by the dotted lines of Figure 3, the ratchet wheel 25 and the hand wheel 15 connected with it are caused to rotate by means of the pawl 27 through a part of a revolution, sufficient to advance the grinder for further grinding. This turning of the hand wheel imparts rotary movement to the shaft 14 with a resultant advancement of the motor on the platform. As the motor is advanced the grinding wheel covers more of the boss until finally the entire surface of the boss is ground away as a plane.

After the highest boss has been ground away to the level of the next higher boss or bosses, the platform 11A and its motor 12 and grinder 13 are set up by the screw 17A, and the grinder may now contact with several bosses of like height. Several such bosses may be ground at one time without danger of breaking the grinder, and the motor and grinder can be swung a greater distance, having regard to the fact that the amount of traverse is controlled by the amount of swing, and that the grinder must not be advanced too fast, to take off too much material at each bite. If the traversing movement of the grinder is to be from the inside towards the outside, the hand wheel 15 is turned to bring the motor and grinder in-

side (to the left, as seen in Figure 3), and the swinging operation described is repeated. The grinder rapidly and repeatedly contacts now with several bosses of like height, and 5 in effect moves outward gradually across them, as the traversing movement effected by the screw 14 increases the effective radial distance of the grinder's working face from the axis of the shaft 8.

10 Finally all the bosses are brought down to the same level, the top of each one plane, and each top lying precisely in a single plane which is perpendicular to the longitudinal axis of the fuselage, though some may project farther from the engine ring 2 than others. The grinding may stop here, or if 15 for any reason it is desired to grind farther, the tool is set up with the screw 17A, and the entire operation repeated.

20 While I have shown a particular form of embodiment of my invention, I am aware that many minor changes therein will readily suggest themselves to others skilled in the art without departing from the spirit and scope 25 of my invention. Having thus described my invention, what I claim as new and desire to protect by Letters Patent is:—

1. In a tool for performing a grinding operation of the type described, the combination 30 of a frame, a platform swingably mounted with respect to said frame, a motor driven grinding wheel mounted for traversing movement on the platform, a screw for moving said grinding wheel with respect to the platform,

35 a gear train interconnecting the screw with the frame whereby oscillatory movement of the platform will cause the grinding wheel to feed toward the work to be dealt with.

2. In a device of the class described, the 40 combination of a frame adapted to be mounted to the fuselage of an airplane, a shaft extending outwardly from said frame, a platform rotatably mounted on said shaft, a motor driven grinder mounted on said platform 45 and a screw for adjusting said grinder transversely of the platform, a gear wheel stationary with said shaft, a gear train interconnecting with said stationary gear to rotate and advance the said screw upon oscillating the 50 platform.

3. In a grinding tool for the purpose described, a support, means for supporting the same from a fuselage, means for adjusting the same with reference to a plane perpendicular 55 to the longitudinal axis of such fuselage, a grinder, means supporting said grinder from said support for movement of its working face in a given plane, which plane by the adjusting means referred to can be made to coincide with a selected plane at right angles to the longitudinal axis of the fuselage.

4. A grinding tool as in claim 3, the grinder support including means to move the grinder 60 in two directions in its plane of movement,

to traverse the working face thereof in such plane.

5. A grinding tool as in claim 3, the grinder support including a platform oscillatable about an axis parallel to the longitudinal axis 70 of the fuselage, and a slide upon which the grinder is mounted, and which is traversable upon said platform to alter the radial distance from the working face of the grinder to the axis of oscillation. 75

6. A grinding tool as in claim 3, the grinder support including a platform oscillatable about an axis parallel to the longitudinal axis 80 of the fuselage, and a slide upon which the grinder is mounted, and which is traversable upon said platform to alter the radial distance from the working face of the grinder to the axis of oscillation, and means operable by the oscillatory movement for traversing 85 said slide relative to the platform.

7. In a grinding tool for the purpose described, a supporting shaft, means to adjust the same with reference to the longitudinal axis of a fuselage, a grinder, a platform carrying said grinder and oscillatably supported upon said shaft to swing the grinder with its line of working contact always in a plane perpendicular to the longitudinal axis of the fuselage, a motor driving the grinder, and means supporting the grinder and itself supported upon said platform for movement relative thereto to move the grinder, in the plane heretofore mentioned, nearer to or farther from the axis of said shaft. 95

8. A grinding tool as in claim 7, the grinder being movable along a chord of its arc of swing, from an outward limiting position inwardly towards a radius, or the reverse. 100

9. A grinding tool as in claim 7, and means including a ratchet drive, and operable by oscillatory movement of the platform, to automatically traverse the grinder. 105

10. A grinding tool as in claim 7, a gear fixed to the supporting shaft, a screw journaled in the platform and threaded in the immediate grinder support to traverse the same, and a gear train and ratchet means operatively connecting the gear upon the shaft and said screw to advance the same as the platform is oscillated. 110

11. A grinding tool as in claim 7, and means upon the shaft for advancing the platform and associated parts axially of the said shaft. 115

In testimony whereof I affix my signature. 120
